United States Patent Office

Des. 198,526
Patented June 30, 1964

198,526

BUS

Friedrich K. H. Nallinger, Stuttgart, and Hermann H. F. Ahrens, Stuttgart-Vaihingen, Germany, assignors to Daimler-Benz Aktiengesellschaft, Stuttgart-Unterturkheim, Germany

Filed Sept. 13, 1963, Ser. No. 76,590

Claims priority, application Germany Mar. 13, 1963

Term of patent 7 years

(Cl. D14—3)

FIG. 1

FIG. 2

FIG. 3

FIG. 5

FIG. 4

FIGURE 1 is a perspective view of the bus embodying our new design;

FIGURE 2 is a front view thereof;

FIGURE 3 is a side view thereof;

FIGURE 4 is a rear view thereof, and

FIGURE 5 is a top plan view thereof.

The essential features of the design reside in the portions shown in full lines.

We claim:

The ornamental design for a bus, as shown and described.
